CARBON AND SOOT ELIMINATOR FOR
OIL BURNERS

Louis C. Trosky, Chicago, Ill.

Application February 26, 1942, Serial No. 432,400

1. Claim. (Cl. 158—92)

This invention relates to improvements in oil burner equipment and, more particularly, to a carbon eliminator in the form of an air supply means which will be simple in construction, economical in manufacture, and highly efficient in use.

Another object of this invention is to provide in oil burners, means for completely mixing the carbon content of the fuel supply within the fire pot so as to allow a maximum travel of said combustible admixture of air and carbon content of the fuel oil supply within the fire pot.

Still another object of my invention is to provide means for producing a sweeping action of the incoming air over the floor area of the fire pot so that the vaporized carbon content of the fuel will be promptly mixed with air and hence not starve for oxygen.

A further object of the invention is to provide means for producing a spiral flame starting closely adjacent the base of the fire pot so as to completely admix the carbon content of the vaporized fuel oil and the incoming air in the flame area.

Other novel aspects and advantages of the invention tending to eliminate carbon deposit on oil burner equipment reside in certain details of construction which will become apparent in the light of the drawing, in which:

Fig. 1 is an elevational view of an oil burning heating unit partly broken away to display the burner structure embodying the present invention;

Fig. 2 is an enlarged fragmentary perspective view of the burner elements illustrated in Fig. 1;

Fig. 3 is a cross sectional detail view through one of the branches of the distributor head as seen along line 3—3 in Fig. 2;

Fig. 4 is a sectional detail view of a burner structure, partly in elevation and showing a modified form of my invention; and

Fig. 5 is a top plan view of the air supply head of my modified form, shown in Fig. 4.

My new burner structure is adapted for use with the conventional oil burner units such as the one in Fig. 1 in which there is provided a jacket 10 within which there is arranged a combustion chamber 11 having communication at its upper extremity with a breeching (not shown) for conveying fumes, smoke and the like to a stack.

Arranged in the bottom wall of the chamber 11 is a fire pot 12. The present disclosure illustrates a cylindrical shaped pot 12, although it is to be understood that my invention contemplates the use of any form of fire pot, as will later become apparent. The pot 12 may be of the conventional type marketed at the present time and including

a bottom wall 13 adapted to support a cylindrical side wall which in turn supports at its open upper end a ring 14 having an opening 15 formed therein to permit emission of the flame from the fire pot 12 into the combustion chamber 11.

A fuel supply pipe 16 enters the fire pot 12 closely adjacent the floor of the pot formed by the upper surface of the bottom wall 13. This supply pipe is in the form of tubing which extends exteriorly of the jacket 10 and into a float valve unit 17 for controlling the flow of fuel into the fire pot 12. Fuel oil is supplied to the float valve unit 17 through a conduit 18 extending from a fuel supply tank 19.

15 The air supply means is generally indicated at 20 and includes a forced draft unit 21 comprising a motor 22 for driving a blower 23 including a fan means (not shown) within a blower housing 24. The blower is adapted to draw air in laterally through a grille 25 and force such air centrifugally from the housing 24 in a stream confined within a tubular casing 26. I provide a flexible tubular casing 26 so that variations in installation may be compensated without difficulty. The air supplied by the blower 23 and directed through the casing 26 ultimately reaches the fire pot 12 as is true of devices which have been heretofore known. However, my invention contemplates a distribution of the air supply as uniform and as free from violence as is possible and obtain from the forced draft the maximum efficiency required to completely consume the carbon content of the fuel.

To accomplish the foregoing advantages, I provide a novel distributor head 27 for the air supply. This distributor head 27 is installed in the fire pot 12 by drilling a hole 28 in the bottom wall 13. A threaded nipple 29 is inserted into the hole 28 and a gasket 30 placed over the nipple on both sides of the wall 13. A threaded nut 31 is screwed upon the threaded nipple 29 from above, while a similar nut 32 is screwed upon the nipple from below, each of these nuts 31 and 32 being tightly screwed against their respective gasket elements 30 so that a perfect seal results, a substantial number of threads being exposed above the top nut 31 so as to receive the hub portion 33 of the distributor head 27. The hub portion 33 is in the form of a cap having inside threads adapted to be screwed down upon the top nut 31 and to act as a lock nut for the latter. Means for conveying the air supply from the hub 33 radially with respect thereto comprises a plurality of equally spaced tubular elements 34. The outside ends of these tubular elements 34 are capped as at 35 and the inner end is threaded into a threaded opening 36 formed in the side wall of the hub 33. The

lower end of the nipple 29 has an elbow 37 threaded thereon, which elbow 37 is normally disposed with its open end exposed to receive the open end of the tubular casing 26 whereby the air from the blower 23 will be conducted up into the distributor head 27.

The radially extending tubular elements 34 are shown as four in number. However, while four of such elements are sufficient for smaller fire pots, when the diameter of the pot is larger and a greater floor area is to be served with incoming air, it is obvious that the number of elements 34 employed are increased accordingly. The number of elements 34 employed would be such number as are required to blanket the lower area of the fire pot 12 with fresh air so as to provide a quantitative supply of air proportional to the carbon content of the fuel for the reason pointed out in the objects heretofore mentioned.

Each of the tubular elements 34 has aligned apertures 38 formed therein. These apertures 38 are relatively small openings serving to distribute the air and to produce a fine spray of air in the lower region of the pot 12. As is illustrated, Figs. 2 and 3, the apertures 38 are disposed to emit air in an oblique direction, thus creating a spiral draft within the fire pot, resulting in a longer flame within a shorter vertical distance, it being understood that the mixing process of air and fuel carbon content of the fuel oil should be completed within the confines of the fire pot 12. The distributor head 27 is disposed as close to the floor of the fire pot as is permissible and as is well known in the art, the fuel oil trickling onto the floor of the burner is preheated, thus gasifying the fuel and providing a readily combustible element immediately upon admixture with the air. The spray of air provided at the apertures 38 permits the mixing of air and fuel carbon at the lowest possible level in the burner and as a result thereof the flame begins at the point of injection of the air, it appearing as though the fuel were emitting from the apertures 38 by reason of a blue flame having its origin therefrom. The entire surface of the floor 13 is served with air from the fine spray emitting from the apertures 38, and the flame originating therefrom spirals its way out through the opening 15 at the upper end of the fire pot 12. It is important to note that by the distributor head provided, there is not a violent entrance of air into the fire pot but rather the air is restricted by the small apertures and broken down into small streams so that the oxygen content of the air is easily and readily mixed with the gasified hydrocarbons rising from the pre-heated pool of fuel oil.

I have shown in Figs. 4 and 5 of the drawing a modified form of distributor head 40, which form is preferably in cases of large types of fire pots. Keeping in mind the salient object of this invention, in the use of a distributor head of the radial type (Fig. 2) in the larger type fire pot and having the termini of its tubular elements 34 spaced at such a distance apart, caused by the increased diameter of the pot 12, certain areas intermediate such termini may not be properly serviced with fresh air which would result in a starving of the fuel carbon, permitting the fuel to ascend well toward the open end 15 of the pot 12 before combustion takes place. If such were the case the flame would extend higher into the combustion chamber, resulting in an increased stack temperature and consequently a loss of efficiency in heat transmittal to the heater chambers of the unit 10. Likewise, a portion of the carbon

content of the fuel would enter so far into the combustion chamber before being completely consumed as to produce soot and a carbon deposit upon the burner unit.

The modified form of my invention embodies the same elements employed in the preferred form with the exception of the shape of the tubular element 34. Instead of radially extending arms such as the elements 34, I have shown a single tubular element 44 which communicates with the hub portion 33 as at 46 and then is coiled about the latter with each successive convolution of the coil substantially equidistant from the other in a direction radially with respect to the hub portion 33. The end of this element 44 is capped as at 45 and is curved to lie a decreased radial distance from the hub 33 than would the normal coil curve so as to terminate substantially nearer to the adjacent convolution 47 (Fig. 4). Apertures 48 are formed in the tubular element 44 equidistant from each other and along a line of the spiral. The apertures 48 are disposed so as to direct the flow of air inwardly and upwardly and at a slight pitch, resulting in a spiral flame similar to that shown in Fig. 1. By this arrangement, regardless of the diameter of the fire pot 12, the entire floor thereof will be serviced with air in the fine spray contemplated so as not to create a violent updraft but rather a steady uniform flow of equally distributed air, the oxygen content of which readily mixes with the carbon content of the fuel oil substantially close to the bottom of the fire pot.

Having thus described my improved burner construction, it is to be noted that by reason of the structure disclosed the entire floor area of the fire pot is blanketed with fresh air, resulting in a mixing of fuel gas with oxygen at the lowest possible point. As a consequence of this the flame travel is practically confined within the walls of the pot 12, resulting in the complete consumption of carbon before it passes off into the broad area of the combustion chamber. The ultimate result of these events is an elimination of carbon and soot, leaving the fire pot 12 and other surfaces exposed to the fire clean and free from particles usually collected in burner units.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

Having thus described my invention, what I claim as new and desire to protect by Letters Patent is:

In an oil burner comprising a fire pot having a fuel retaining bottom wall and an air supply conduit entering said fire pot, means for supplying liquid fuel to said pot, means for mixing air with said fuel at the lowest possible level in said fire pot, said means including a continuous conduit element in the form of a coil having substantially uniform convolutions, said coil adapted to receive air from said air supply and having a plurality of equally spaced apertures formed therein along the upper inward surface of said conduit element for directing a relatively fine spray of air inwardly and upwardly over the entire area of said bottom wall.
